[57] CLAIM

The ornamental design for a diaper pants, as shown and described.

DESCRIPTION

FIG. 1 is a front elevational view of a diaper pants, showing our new design in stretched condition;

FIG. 2 is a left side elevational view thereof, the right side elevational view being identical thereto;

FIG. 3 is a top plan view thereof;

FIG. 4 is a rear elevational view thereof;

FIG. 5 is a bottom plan view thereof; and,

FIG. 6 is an enlarged cross-sectional view thereof taken along line 6—6 of FIG. 1.
